Application May 17, 1941, Serial No. 393,868

24 Claims. (Cl. 178—44)

1

This invention relates, generally, to the art of high frequency energy transmission and apparatus related thereto, and has reference more particularly, to novel improvements in impedance matching and transforming devices adapted for use with this type of apparatus operating at ultra-high frequencies, of the order of 10^9 cycles per second.

In transforming energy from one high frequency device to another, it is well known that the value of the impedances of the respective devices must be properly matched in order to avoid the production of standing waves with attendant increase in losses and decrease in the energy transmitting capacity of the system. Further, for maximum efficiency, it is known that the impedance of a load or utilization device must be properly transformed to match that of the source.

The present invention is principally directed toward the provision of improved impedance matching and transforming devices which are adapted to efficiently couple and match the impedance values of the circuit elements interconnected thereby with a minimum of adjustment and a maximum of facility and efficiency.

In another of its aspects, the present invention is directed toward a provision of a novel sliding joint utilizable in connection with the above-mentioned impedance matching and transforming devices, or, which may be employed generally in ultra-high-frequency coupling arrangements wherever adjustability and smoothness of transition are desired.

A principal object of the present invention is to provide novel impedance matching means for matching the impedance of an apparatus of the above character to that of other apparatus, such impedance matching means being designed for versatile operation in that it may efficiently connect two impedance elements having impedances of different values with high efficiency of power flow therebetween.

A further object is to provide novel impedance matching means which is so designed as to efficiently match both the resistive and reactive components of any two impedance elements having generally different impedance values.

Another object is to provide novel and efficient sliding joints for telescoping concentric transmission lines, whereby reflections and standing waves are prevented.

A still further object is to provide a novel transmission line section having a cylindrical outer conductor and an eccentrically and adjustably positioned inner conductor.

Other objects and advantages will become apparent from the specification taken in connection with the accompanying drawings, wherein, Fig. 1 is a view in side elevation and partly in

2

section of an electron discharge tube structure adapted to be used in a high frequency transmitting and/or receiving system wherein the present invention may advantageously be included. An electron discharge tube of the indicated type is disclosed and claimed in a copending divisional application filed in the names of the present inventors and bearing Serial No. 420,771;

Fig. 2 is a perspective view of the fine tuning adjustment of the tube of Fig. 1;

Fig. 3 is a longitudinal sectional view of one type of impedance matching device, or impedance transformer;

Fig. 4 shows a radio transmitting system incorporating the tube of Fig. 1 and the impedance transformer of Fig. 3;

Fig. 5 is a view partly in section of a detail of Fig. 4;

Fig. 6 is a sectional view of the antenna and reflector of Fig. 4;

Fig. 7 is a longitudinal section of an alternative type of impedance transformer;

Figs. 8, 9 and 10 are cross-sections of Fig. 7 taken along lines 8—8, 9—9 and 10—10 respectively;

Fig. 11 is a diagram explanatory of the operation of the device of Fig. 7; and

Fig. 12 is a longitudinal cross-section of a further modification of impedance matching transformer.

In the drawings, Fig. 1 shows an electron discharge tube structure 1 comprising an indirectly heated cathode 2 having a heater 3, a modulating grid 5 and spaced, cylindrical, resonators or resonating chambers 7, 9, 11. These resonators have rigid dished walls 13, 15, 17 and opposed flexible walls 19, 21, 23, respectively, the dished walls being centrally apertured and provided with grids. Flexible walls 19 and 21 of resonators 7 and 9 are joined by a drift tube 25 also having grids at its ends opposite the grids of walls 13 and 15. This tube 25 has a central threaded portion 27 for retaining a thrust plate 29 thereon. The main body 33 of the tube 1 carries a flange 35 which has several threaded holes 37, in this case shown, for illustrative purposes only, as three in number although only two are visible in the showing of Fig. 1. These threaded holes 37 carry thrust screws 39, one end of each of which terminates in a shape suitable for the application of a wrench for turning the screw, or in a slot for receiving a screw driver, while the other end terminates in a socket adapted to receive the ball heads of thrust rods 41, 43. The screws 39 also have lock nuts 45 for maintaining them in their set position. The other end of each of the thrust rods 43 is placed in a socket in the thrust plate 29 similar to the sockets in screws 39. The plate 29 has rigidly fastened to it, as by screws 47, a resilient cantilever leaf member 49. The

member 49 is fastened to plate 29 at one end only, in cantilever fashion. The unfastened end of cantilever 49 is adapted to be moved by the movable stem 51 of a micrometer arrangement 53 mounted as by bracket 55 on plate 29. Rotation of handle 57 results in transmission of thrust to cantilever 49 through ball 59, resulting in deflection of the resilient cantilever 49. Thrust rod 41 is socketed at one end in the member 49 near the fastened end of this member, and at the other end in its screw 39.

Fig. 2 shows plate 29 with rods 41 and 43 in their normal operating position. These rods are held in position in the actual device by the opposition to deformation of the resonating chamber 7 created largely by atmospheric pressure acting on the evacuated casing 33, as described below. While the cantilever tuning means has been shown as applied only to the first resonating chamber, it is obvious that it could equally well be applied to any of the others.

Resonating chambers 9 and 11 have their rigid walls 15, 17 connected together as by peripheral connection member 61, which carries a flange 63 similar to flange 35. Flange 63 carries screws 65 similar to screws 39, which transmit thrust through thrust rods 67 to plate 29. Resonator 11 has its flexible wall centrally apertured and carries a tube 71 terminating in outer cooling fins 73. Mounted on this tube 71 is another thrust plate 75 carrying thrust screws 77 bearing against thrust rods 79 which in turn bear against flange 63, the usual lock nuts 81 being provided.

Each of the resonating chambers 7, 9, 11 has provided means for supplying or abstracting high frequency energy in the form of concentric line terminal posts 83 whose inner conductors terminate in coupling or pick-up loops 85.

In operation, electrons emitted by the cathode 2 form a beam which may be modulated by supplying suitable potentials to grid 5. The electrons are accelerated by the potential difference between cathode 2, usually maintained at a high negative potential, and rigid wall 13, which acts as an accelerating electrode and is usually grounded. As is well known, the passing of the beam through the first resonating chamber 7, known as the "buncher" effects recurrent changes in velocity of the electrons of the beam. Passage of electrons through the drift tube 25 permits the electrons to bunch, and to give up their energy upon passage through the second resonator 9, known as the "catcher." Output energy can be obtained from the resonator 9. However, in order to prevent the abstraction of energy from affecting the frequency characteristics of resonator 9 and of resonator 7, which may, in some applications of the device, be coupled to resonator 9, the electron beam, now "bunched," is allowed to pass through the further resonator 11, and output energy is obtained from this resonator, which cannot reflect back into the other resonators 7 and 9 to change their frequency characteristics since it is coupled to the other resonators only by the electron beam. The novel tube of this invention thereby includes a buffer stage or resonator as well as the "buncher" and "catcher" stages or resonators.

As is well known, the frequency of operation of such devices as the present depends on the size and shape of the resonating chambers. The present invention provides means for adjusting the frequency of each of the resonators. Thus, it is clear that turning screws 77 will create a thrust between plate 75 and flange 63, which will be

transmitted to the rigid wall 17 and the flexible wall 23 of resonator 11 to create relative thrust therebetween. This thrust is opposed by the action of atmospheric pressure on the evacuated chamber, which tends to collapse the flexible wall. This adjustment of screws 77 therefore causes deformation of the flexible wall 23, thereby changing the resonating frequency of this resonating chamber. Once adjusted, the frequency may be maintained by use of the lock nuts 81 to maintain screws 77 in desired position.

Turning screws 65 will in like manner create relative thrust between the rigid and flexible walls of resonator 9 and cause tuning of this resonator. It will be noted that this tuning cannot affect the tuning of resonator 11, since no thrust is created between the rigid and flexible walls of that resonator by turning screws 65. At most, a slight motion of the whole resonator 11 occurs, due to deformation of flexible wall 21 of resonator 9.

In the same manner, the frequency of resonator 7 can be adjusted by screws 39. Here again, no effect is produced on either of the other resonators. It is obvious that the tuning of each of the resonators is independent of any other, and the resonators may be adjusted in any desired order.

In the case of resonator 7 there is further provided the novel fine cantilever adjustment for tuning above described. It will be seen that turning micrometer handle 57 will create a thrust on resilient cantilever 49 through ball 59. This thrust is transmitted to rod 41 by the cantilever action of member 49 and thence to resonator chamber 7. A dual refinement of tuning is obtained by this means. First, there is the refinement by use of a micrometer screw instead of the ordinary screws 39. There is a second refinement in tuning by use of the cantilever arrangement, even over an ordinary rigid lever arrangement. If an ordinary lever were used, pivoted at screws 47, the motion of rod 41 would be reduced relative to that of micrometer rod 51 by a factor which is proportional to the ratio of their relative distances from the pivot. The novel method here used obtains a further refinement over such a pivoted lever arrangement, since the reduction in deflection of rod 41, using the cantilever arrangement and neglecting the opposing force created by rod 41, is by a factor roughly proportional to the square of the ratio of the relative distances, since the cantilever assumes a roughly parabolic shape. Furthermore, the effect of the opposition of rod 41 to being moved by the application of force to the end of the cantilever 49 is to further reduce the relative motion, and to effect further refinement of tuning. From another point of view, this results in further curvature of the cantilever spring, making the deflection of rod 41 proportional to the applied motion by a factor which is inversely proportional to even higher powers of the distance ratio than the second power. It will be seen thus that extremely fine and sensitive tuning adjustments can be made, which is essential for successful operation, especially in small tubes operating at high frequency, where the slightest change in size and shape produces extremely large changes in resonating frequency.

Fig. 3 shows a concentric line impedance matching device or transformer 87 suitable for connecting the tube of Fig. 1 to any load and with maximum effect. Such a connection is shown in Fig. 4, which shows the tube connected to an antenna 89 by means of impedance transformer 81.

The transformer 87 is illustrated as comprising a central sleeve 91 in which are mounted the ends of spaced concentric transmission lines 93, 95 whose outer conductors are permanently connected to sleeve 91 and whose inner conductors extend radially inwardly of this sleeve 91. These lines may be open stub lines or terminal posts having their remote ends adapted for connection to other transmission lines or loads. Two cylindrical end members 97, 99 are carried by or formed in sleeve 91. The members 97, 99 are bored to a suitable diameter for receiving a slideable shorting plug 101 carrying a reduced rod 103. The size of the bore in member 99 and the diameter of rod 103 are suitably chosen to form an efficient concentric transmission line. The remote end of rod 103, shown reduced, is threaded as at 105. Upon this threaded portion is screwed shorting plug 107, which fits snugly but slidably in the bore of member 97 and has an enlarged portion 109 serving as a knob whereby the distance between the inner faces of plugs 101 and 107 may be varied by turning knob 109, and the entire unit composed of plugs 101 and 107 and rod 103 may be slid back and forth longitudinally within outer members 97, 99 and sleeve 91, by longitudinal translational motion of knob 109.

Rod 103 slides within a fixed sleeve 111, whose outer diameter is so selected that it bears the same ratio to the inner diameter of sleeve 91 as the diameter of rod 103 does to the bore of members 97, 99. Sleeve 111 is permanently connected to the inner conductors of transmission lines 93, 95 and is therefore immobile with respect to sleeve 91 and members 97, 99. Sleeve 111 tapers down to the size of rod 103 at its end proportions, as shown. Members 97, 99 have a corresponding internal taper. These tapers are so chosen as to maintain constant the ratio of the sizes of outer diameter of the inner conductor to that of the inner diameter of the outer conductor, thereby preserving substantially constant characteristic impedance for all sections of this concentric line element.

The method of operation is as follows: knob 109 is turned until the distance between the inner faces of shorting plugs 101 and 107 is approximately one-half wave length at the operating frequency. Then the whole inner portion, comprising rod 103 and plugs 101 and 107, is slid back and forth until the proper match is obtained. At the optimum point, the device connected to line 93 in parallel with the short circuited stub line to the left of the connecting point of line 93 is matched, over the section of line between the connecting point of 93 and that of 95, to the device connected to line 95 in parallel with the short circuited stub line to the right of the connecting point of 95.

The impedance transformer of Fig. 3 will match, with certain limitations, a device of any impedance value to another device of any impedance value connected therethrough. It is perfectly symmetrical in action; that is, when a lower impedance value is to be matched to a higher impedance value, the device having either one may be connected to either terminal of the impedance transformer.

Fig. 4 shows an arrangement using the above impedance transformer in which resonator 9 is coupled back to resonator 7, as by transmission line 112, thereby causing tube 1 to generate oscillations. The output of tube 1 is taken from buffer resonator 11 by means of transmission line 113 to preserve stability of oscillation, and is connected,

by means of phase adjuster 117, impedance transformer 87 and transmission line 115, to a load shown as antenna 89. This figure shows an electron discharge tube 1 of the type described above, coupled to an antenna 89 by means of transmission lines 113 and 115, phase adjuster 117 and impedance transformer 87. In tube 1, resonator 9 is shown coupled back to resonator 7 by line 112, to provide oscillations. Transformer 87 and phase adjuster 117, which is of the sliding joint type further described below, are shown as mounted on a base 119 by means of bracket 121 which holds the impedance transformer 87 and the fixed part 93 of the phase adjuster 117. The movable part 114 of the phase adjuster 117 is connected to screw 123 by a member 125. The screw 123 is threaded into the bracket 121, so that rotation of the screw 123 will produce relative motion between the two parts of the phase adjuster 117. Transmission line 113 is connected directly to the buffer stage output of tube 1 and is connected to the input of impedance transformer 87 by means of the sliding joint of phase adjuster 117 more fully described in connection with Fig. 5. As an illustrative example, let us take the output impedance of the tube 1 to be 30 ohms. Then, transmission line 113 may be modified by the variable section of phase adjuster 117 to be a half-wave (or multiple of a half-wave) line, so that the impedance at the input of the transformer, looking back at the tube, will also be 30 ohms. The transformer is then adjusted to transform this value of impedance to some value such as 72 ohms, and then a 72-ohm line (i. e. line 115) is connected to the output of the transformer. This 72-ohm line 115 is then shown connected to a 36-ohm quarter-wave antenna 89 by means of a matching section 133 shown more in detail in Fig. 6.

The sliding joint phase adjuster of Fig. 5 has a fixed part 93, with inner conductor 131, and a sliding part 114, with inner conductor 129, and relatively movable by means of screw 123. With the ordinary type of sliding joint it is almost impossible to avoid wave reflection because of the discontinuities involved. The joint of Fig. 5 is designed to avoid these reflections. The inner conductor 129, which slides over the inner conductor 131, is extended one-quarter wave length beyond its outer conductor 114. Furthermore, the relative dimensions of conductors 129 and 93 are so chosen that the section of line between points P and Q has a characteristic impedance which is the geometric mean of the impedances of each of lines 93 and 114. Methods for calculating the dimensions of transmission lines to obtain a given impedance are taught in standard textbooks, such as "Radio Engineering," by F. E. Terman (2d edition, p. 698). In this way, the extended portion of conductor 129 forms with the outer conductor 93 a quarter-wave matching line which causes lines 93 and 114 to be matched perfectly without reflections occurring.

Fig. 6 shows a tapered line section 133 for matching the line 115 to the quarter-wave antenna 89. In the example used above, this line section 133 would have to match the 72-ohm line 115 to the 36-ohm antenna 89. This section 133 is one-half wave length long, and has an exponential variation of impedance with length. Therefore, the diameter of the inner conductor varies as an exponential function of an exponential function of the distance along the line section.

The variation of inner diameter shown in Fig. 6 is that needed for matching in the illustrative

example used. For matching other values of impedance the profile of the inner conductor may be concave, instead of convex as shown, or may be both concave and convex with a point of inflection, depending on the particular values of impedance to be matched.

The explanation of the operation of this line section to prevent reflections and standing waves is similar to that of the usual quarter wave line section. In such a quarter wave section, a traveling wave will set up a reflection at the beginning of the section. The unreflected portion will travel quarter-wave length further and set up a second reflected wave at the discontinuity at the end of the section. This second reflected wave will travel back quarter-wave length and will then be out of phase with the first reflected wave and hence the two reflected waves will neutralize, provided the proper amplitude relations are observed. This is insured by having the characteristic impedance of the quarter-wave length section equal the geometric mean of the two impedances to be matched.

The present half-wave length section operates in a similar manner; that is, the reflected wave at the end 128 of the half-wave length section 133 is used to neutralize the wave setup at the beginning 129 of the section 133. One important difference exists here: in the case of the ordinary quarter-wave length section, the change in impedance at the points of discontinuity is in the same direction at both ends of the line section; that is, both have increasing impedance values or both have decreasing impedance values. In the case of the present section 133, the types of discontinuity are opposite; that is, there is a break from constant impedance to varying impedance at 130, and then a second break from varying impedance to constant impedance at 128. This introduces an additional 180 degrees phase shift between the two reflected waves. Hence, for neutralization, the line must be half-wave length (or 180 electrical degrees) long, so that adding up the phase shifts caused by the direct wave travel time, the reflection, and the reflected wave travel time will result in phase opposition. The proper amplitude relations are observed by having an exponential variation of impedance along the section 133. Since impedance varies as the logarithm of the ratio of outer conductor diameter to inner conductor diameter, and since the outer conductor 133 is constant in diameter, this necessitates a doubly exponential variation of the diameter of the inner conductor 132.

Figs. 7 to 10 show an alternative form of impedance transformer which will operate to transform or match the impedance of a fixed impedance element into any desired impedance value. It may serve to match a device having an arbitrary impedance value with that of a particular concentric transmission line. This matching transformer has an inner conductor 135 which has an intermediate offset portion 137 at least three-quarters of a wave length long. Fixed to the inner conductor 135 are two sleeve portions 139, 141 fixedly joined to the inner conductor 135 by insulating members 143. Slidably mounted within sleeve 139 and outside of conductor 135 is a conducting sleeve 145 maintained electrically separate from conductor 135 by insulating member 147. The insulating member 147 slides on conductor 135 and is fixed to sleeve 145. Obviously, member 147 could just as well be fixed to conductor 135 and slide in sleeve 145. A sleeve

149 is similarly arranged within sleeve 141. Sleeves 145 and 149 have thin-walled sections 144 and 150 extending away from the center of the device. These thin-walled sections are exactly one-quarter wave length long and so dimensioned that, analogous to the device of Fig. 5, the thin-walled sections act as quarter-wave matching lines between the terminal line and the line composed of sleeve 145 (or 149) and conductor 135, the characteristic impedance of these matching lines being equal to the geometric mean of the impedances of the lines immediately connected thereby. Each of these sleeves 145 and 149 has a tapered portion 151 which may be slotted axially. Fixedly attached to sleeves 145 and 149, are threaded rings 153. These engage with clamping rings 155 having a tapered portion mating with tapered portion 151, whereby, upon threading clamping ring 155 on ring 153, the tapered portion 151 is clamped against sleeve 145 or 149, serving to keep rings 139 and 145, or 141 and 149, in their adjusted positions. Sleeves 145 and 149 are joined by an eccentric yoke member 157. Sleeves 145 and 149 may have flanged ends as at 159. Yoke 157 is provided with threaded portions 161 which cooperate with rings 163 to prevent sleeves 145 and 149 from any relative axial motion, while leaving yoke 157 free to rotate. The portion of yoke 157 which cooperates with offset portion 137 of the inner conductor is exactly one-quarter wave length long.

Inner conductor 135 and sleeve 139 (or 141) may have any relative sizes, but are preferably so proportioned as to constitute one of the usual concentric transmission line sizes. The portion of the transmission line formed by the offset inner conductor 137 and sleeve 145 (or 149) is proportioned to have the same impedance as the portion of line constituted by inner conductor 135 and outer conductor 139 (or 141), so that no losses or reflections will be encountered at the junctions of offset and regular portions. The effect of offsetting the inner conductor of a concentric transmission line is to increase its capacitance and therefore to decrease its characteristic impedance. The effect of decreasing the diameter of the inner conductor of a concentric transmission line is to increase its characteristic impedance. Hence, the diameter of the offset portion of the inner conductor is reduced by the amount necessary to compensate for the decreased characteristic impedance caused by offsetting, leaving the net impedance the same.

The diameter of the eccentric opening in yoke 157 is adjusted so that at the most eccentric position of the rotation of yoke 157, the yoke just touches the offset inner conductor 137, as shown in Fig. 9, and at the other extreme of rotation the inner conductor 137 is concentric with the sleeve opening, as shown in Fig. 8. For other degrees of rotation there will be spacings of inner conductor 137 with respect to yoke 157 varying from that shown in Fig. 9 to that shown in Fig. 8.

End caps and adapters 165 for connecting the device to standard concentric transmission lines are provided, using the proportional taper explained in connection with Fig. 3.

The operation of the device of Fig. 7 can best be explained on the basis of the diagram of Fig. 11. This figure shows, on an impedance diagram whose coordinate axes represent resistance and reactance, the constant-coordinate lines of a bipolar coordinating system having poles such as Z_0 . Only the right half of this diagram is shown, the left half being a mirror image of the

right. These constant-coordinate lines form two families of circles, one family with centers on the X-axis (axis of reactance) and passing through both poles and the other family having centers on the R-axis (axis of resistance) such that each circle of one family crosses every circle of the other family at right angles. This system, therefore, forms an orthogonal curvilinear coordinate system known as the bipolar coordinate system. It can be shown that, if the poles of such a system are chosen to be the points representing the characteristic impedance of a transmission line, and if an arbitrary impedance value is selected, such as represented by point Z on Fig. 11, and connected to varying lengths of the transmission line, then the net impedance, looking from the remote end of the transmission line to impedance Z, is represented by points moving along the constant-coordinate circle ZR_1R_2 passing through Z. This impedance locus makes one complete rotation around Z_0 , back to Z, for each half wave-length of line added. Thus we see that, in order to tune impedance Z to resonance, enough line must be added to carry the net impedance to point R_1 . This would give a high resistance resonance condition. If more line is added, we finally reach a low resistance resonance point R_2 .

The above theory is used in the operation of the device of Fig. 7. Let us assume, for illustrative purposes, that sleeve 139 and conductor 135 make up a 72 ohm line. It is desired to match a 72 ohm line to any arbitrary value of impedance, not necessarily purely resistive. The 72 ohm line is connected to the left end of the impedance transformer, which it matches since it has been assumed that this left end constitutes a 72 ohm line. The element having any arbitrary impedance value is connected to the right end of the device. The length of transmission line between the element of arbitrary impedance and the beginning of eccentric sleeve 157 is then adjusted by sliding sleeve 149 within sleeve 141 until the value of arbitrary impedance plus that of the line, looked at from the beginning of the eccentric sleeve 157, exhibits minimum resistive impedance. This corresponds to transforming the point Z (Fig. 11) to point R_2 by adding a length of line corresponding to the heavy arc ZR_1R_2 . If we look to the left from the left edge of the eccentric sleeve 157, there is also exhibited a pure resistance, since everything connected to the left end of the transformer is matched. This resistance however, is not R_2 but Z_0 . There remains the step of matching two purely resistive impedances of different values. This is done by rotating the eccentric sleeve 157 to the proper position, which will be that at which the quarter wave length line 157 exhibits a resistive impedance R_3 equals $\sqrt{R_2Z_0}$, i. e., the geometric mean of the two impedances to be matched.

Since the sleeve 157 constitutes a quarter-wave length line, its impedance will always be resistive. Rotating the sleeve will vary the position of the inner conductor 137 relative to the outer conductor (sleeve 157) from that shown in Fig. 8, which has maximum resistance, to that shown in Fig. 9, which has zero resistance. If the eccentric sleeve opening is properly proportioned relative to the diameter of offset inner conductor 137, the quarter wave length line can exhibit any resistance from zero to a value at least as large as Z_0 , so that by properly positioning the sleeve, the required resistance, such as

R_3 (Fig. 11) can easily be obtained, providing substantially perfect matching.

Fig. 12 shows another embodiment of impedance transformer which also can match the impedance of any impedance element to that of any other impedance element. This embodiment comprises a concentric line device having an outer cylindrical conductor 167 in which is fastened a perpendicular sleeve section 169 of equal diameter. Supported within conductor 167 as by insulator 171 is a concentric inner conductor 173 which also has a perpendicular section 175 of equal size which is concentric with section 169. A reducing end cap having tapered portion 177 similar to 165 in Fig. 7 is provided for coupling this device to a standard line or other impedance. The diameter of the concentric line section forming the impedance transformer is made larger than the line to which it may be coupled in order to increase efficiency of operation.

Sliding within sleeve 169 is a movable shorting disc or plunger 179 moved by plunger rod 181. The shorting disc 179 carries spring fingers 183 which make good electrical contact with conductors 169 and 175 while permitting sliding motion. Sliding within sleeve 167 is sleeve 185. Fastened concentrically within sleeve 185, as by insulator 187, is sleeve 189 which has an inner diameter chosen to give sliding contact with rod 173. An end cap and tapered section 177 is also provided for this end of the device.

Inner sleeve 189 ends one quarter of a wave length within the end of sleeve 185. The portion of sleeve 185 not opposite sleeve 189 (that is, the last quarter wave length) has a thickened wall, formed in this instance by inserting sleeve 191 permanently fastened to sleeve 185. The dimensions of conductors 167, 173, 191, 185 and 189 are so chosen that the characteristic impedance of the 191-173 section of line is equal to the geometric mean of the characteristic impedances of the 167-173 and 185-189 sections, thereby avoiding reflections at the sliding joint, as discussed above.

Accordingly, an impedance matching transformer has thus been provided whereby any pair of arbitrary impedance values may be matched by adjustment of the length of a section of concentric transmission line connected in cascade with one of the arbitrary impedance values and by the subsequent adjustment of the length of a short-circuited section of concentric transmission line connected in parallel with the cascade-connected transmission line section. It is understood that the order of these adjustments is immaterial.

The theory and method of operation of the device of Fig. 12 may be explained on the basis of a diagram similar to Fig. 11, but wherein the coordinate axes represent susceptance B and conductance G rather than reactance X and resistance R so that the diagram represents admittance Y rather than impedance Z. Such an admittance diagram would have the same bipolar coordinate system as shown in Fig. 11, but the poles would be the characteristic admittance

$$Y_0 \left(\text{equal to } \frac{1}{Z_0} \right)$$

instead of characteristic impedance Z_0 . For simplicity, Fig. 11 will be used again, it being understood that, wherever the symbol Y is used, the admittance diagram is meant.

Now, if it is desired to match two loads having admittances Y_1 and Y_2 , respectively, it will be

necessary to match both the susceptances and conductances of these loads. By gradually adding transmission line having admittance Y_0 to load Y_1 , the resulting admittance varies counter-clockwise around the circle Y_1, Y' . By adding sufficient line, the resultant admittance can be made to be Y' , having the same conductance as Y_2 but different susceptance. By adding pure susceptance, we can match the admittances Y_1 and Y_2 , and therefore the impedances, perfectly. Such added susceptance is obtained by varying the length of stub line 169-175, by moving plunger 181 in or out to add the proper amount of susceptance in parallel with the line section 167-173. If the admittance Y_2 should lie wholly to the right or left of the circle traveled by Y_1 , then it is merely necessary to interchange Y_1 and Y_2 ; that is, Y_2 would then be connected to the right end of the device of Fig. 12.

From the above analysis, it is evident that to use the device of Fig. 12, it is merely necessary to connect one impedance element at each end, then vary the length of line at the sliding joint until the conductances become matched, and then vary the shorting plug until the susceptances are matched. Then the impedance values of the two impedance elements will be matched.

As many changes could be made in the above constructions and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A transformer device for matching the admittances of any two circuit elements comprising adjustable means for converting the conductance of one of said elements to a value equal to that of said other element, and independent adjustable means for adding substantially pure susceptance to said converted conductance to fully match said two admittances.

2. Apparatus for matching two circuit elements having any admittance values comprising a section of transmission line of the coaxial conductor type adapted for connection between said circuit elements, means for varying the length of said line section for making the conductance of one of said circuit elements equal to the conductance of the other circuit element, and further means for adding substantially pure susceptance to one of said circuit elements until both circuit elements have the same values of susceptance.

3. An impedance transformer for transforming an arbitrary impedance value to another arbitrary value, comprising an adjustable length section of concentric transmission line adapted to be connected in cascade to said arbitrary impedance value, and an adjustable length of short circuited section of concentric transmission line connected in shunt to said first section intermediate the ends thereof, whereby said other arbitrary impedance value may be obtained by adjustment of the lengths of said two sections.

4. An impedance transformer for matching the impedances of two circuit elements having any impedance values, comprising an adjustable length section of transmission line adapted to be connected in cascade between said elements, and an adjustable length section of transmission line connected in shunt to said first section intermediate the ends thereof, whereby said impedances

may be matched by adjustment of the lengths of said two sections.

5. An impedance matching transformer comprising a section of hollow transmission line having a fixed unitary inner conductor, means cooperating with a section of said inner conductor for providing a line section of adjustable characteristic impedance, and means for axially adjusting the position of said variable impedance section relative to said inner conductor.

6. An impedance matching transformer comprising a transmission line section of the coaxial conductor type having an outer conductor made up of a fixed central section and axially adjustable end sections, and an inner conductor of fixed length extending between said end sections and wherein said inner conductor is formed with an intermediate eccentric portion.

7. An impedance transformer for matching any two impedances, comprising means including an adjustable length section of concentric transmission line connected in cascade with one of said impedances for converting the conductance of said one impedance to a value equal to that of said other impedance, and means including an adjustable length short-circuited section of concentric transmission line connected in parallel with said first section for adding susceptance to said converted impedance to fully match said two impedances.

8. An impedance matching transformer comprising a transmission line section of the coaxial conductor type and of substantially invariant over-all length having an outer conductor made up of an axially adjustable central section having a portion of eccentric bore and relatively fixed end sections for telescopingly receiving said central section upon adjustment of said central section, and an inner conductor of fixed length extending between and fixed to said end sections.

9. Apparatus for transforming any arbitrary impedance value to another impedance value comprising a fixed length of coaxial type transmission line having input and output terminal portions and adapted to be connected at one of said portions to a circuit element having said arbitrary impedance value, adjustable transmission line means having variable characteristic impedance coupled in cascade between said terminal portions and mutually cooperable means at each of said terminal portions for simultaneously and oppositely varying the length of line from one of said terminal portions to said variable characteristic impedance means and the length of line from the other of said terminal portions to said variable characteristic impedance means.

10. An impedance matching transformer for matching a transmission line to any load, comprising means, including an adjustable section of transmission line having a telescoping cylindrical outer conductor and a concentric inner conductor with an off-set eccentric portion, for converting the impedance of said load to a pure resistance, and further means, including a quarter wave section of transmission line having said eccentric conductor as inner conductor and a rotatable outer conductor with a circular bore eccentric to said cylindrical outer conductor, for matching said resistance to the characteristic impedance of said transmission line.

11. An impedance transformer comprising a pair of fixed coaxial outer conductor end pieces, an inner conductor insulatingly fixed to said pair of end pieces and having an off-set portion eccentric to said end pieces, and a sliding member

comprising a quarter wave section of conductor having a bore eccentric to and surrounding said off-set eccentric portion and rotatably fixed between a pair of outer conductor sections slidably engaging said end pieces, whereby, by translation of said sliding member, the reactance of one concentric transmission line, connected to one of said end pieces and said inner conductor, may be matched to that of second concentric transmission line, connected to the other of said end pieces and said inner conductor, and by rotation of said eccentric quarter wave section the resistances of said reactance matched line may also be matched.

12. An impedance transformer as in claim 11 wherein the diameter of said off-set portion of said inner conductor is reduced by the amount necessary to match the impedance of the line formed by said concentric inner conductor and said outer conductor section to the impedance of the line formed by said eccentric inner conductor and said outer conductor section.

13. An impedance transformer as in claim 11 further including means for preventing reflections at said sliding joints, comprising a changed inner diameter of the inner one of said slidably engaged conductors for a quarter wavelength from said joint, said changed diameter being of the proper amount to make the characteristic impedance of the line section comprising said changed diameter of a value substantially equal to the geometric mean of the characteristic impedances of the neighboring sections of concentric transmission line.

14. An adjustable concentric transmission line comprising a first section having an inner conductor and a concentric outer conductor, a second section having an outer conductor adapted to slidably engage the outer conductor of said first section, and having an inner conductor adapted to slidably engage the inner conductor of said first section, one of said conductors of said second section extending a distance equal to a multiple including unity of a quarter of a wave length of the operating frequency beyond the other of said conductors of said second section, whereby a portion of said line is formed by one conductor from each of said sections, the dimensions of said inner and outer conductors being so chosen that the characteristic impedance of said portion has a value equal to the geometric mean of the characteristic impedances of said two sections.

15. The transmission line defined in claim 14, wherein the inner conductor of said second section extends said distance beyond the outer conductor of said second section.

16. An adjustable concentric transmission line comprising an inner conductor, a first sleeve surrounding said inner conductor, a second sleeve surrounding said inner conductor and slidably fitting said first sleeve, the inner diameter of the end portion of the inner of said sleeves being different from the inner diameter of the adjacent portion of said inner sleeve for a fixed distance of substantially one quarter wave length of the operating frequency, the inner diameters of said sleeves and the outer diameter of said inner conductor being so chosen that the characteristic impedance of the section of concentric transmission line which includes said end portion has a value equal to the geometric mean of the values of the characteristic impedances formed by said two sleeves and said inner conductor, whereby no wave reflections are obtained at said sliding joint.

17. A transmission line comprising a hollow tubular outer conductor, a first section of inner conductor substantially concentrically mounted within said outer conductor, a second section of inner conductor comprising a continuation of said first section but eccentric to said outer conductor, and a rotatable portion of said outer conductor having a bore eccentric to the remainder of said outer conductor, said bore being disposed about said eccentric inner conductor section.

18. An impedance matching transmission line device comprising a hollow outer conductor made up of a central portion and telescoping tubes providing end portions adjustable in length, a substantially concentric inner conductor having an intermediate section eccentric with said outer conductor, and a rotatable section of said central portion of said outer conductor having a bore eccentric to said outer conductor and disposed about said eccentric inner conductor portion.

19. A reflection eliminating transmission line joint comprising two sections of transmission line of the coaxial conductor type, means interconnecting said sections for relative axial adjustment, and means comprising an impedance matching section in said line between said two sections, said matching section having a ratio of diameters of inner and outer conductors different from that of said other two sections, and said matching section having a fixed axial length substantially equal to a multiple including unity of a quarter of a wavelength of the operating frequency, which fixed length is maintained during all positions of relative adjustment of said two sections.

20. A reflection eliminating transmission line joint comprising two sections of transmission line of the coaxial conductor type, means telescopically interconnecting the outer conductors of said sections for relative axial adjustment, and means providing an impedance matching section in said line between said two sections, and having a ratio of diameters of inner and outer conductors different from that of said other two sections, said matching section comprising the terminal portion of one conductor of one of said two sections extended coextensive with the corresponding other conductor of the other of said two sections, and said terminal portion having a fixed axial length of one-quarter of the wavelength at operating frequency, or a multiple thereof, which fixed length is maintained during all positions of relative adjustment of said outer conductors.

21. The transmission line joint defined in claim 20, wherein said terminal portion is an extension of one of said outer conductors.

22. The transmission line joint defined in claim 20, wherein said two sections have substantially common inner conductor means, and said terminal portion is an extension of one of said outer conductors.

23. The transmission line joint defined in claim 20, wherein the inner conductors of said two sections are slidably engaged, and said terminal portion is an extension of one of said inner conductors beyond its associated outer conductor.

24. The transmission line joint defined in claim 20, wherein the inner conductors of said two sections are slidably engaged, and said terminal portion is an extension of one of said outer conductors.
